(57) **CLAIM**

The ornamental design for an insulating housing for gas device, as shown and described.

DESCRIPTION

FIG. 1 is a front, top, right side perspective view of an insulating housing for gas device, wherein first and second portions thereof are shown in a mated configuration; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

FIG. 8 is a front, top, right side perspective view of the first portion of the insulating housing for gas device in an unmated configuration;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in the figures show portions of the insulating housing for gas device and its environment that form no part of the claimed design.

1 Claim, 14 Drawing Sheets
